UNITED STATES PATENT OFFICE.

OMAR I. NIGH, OF WASHINGTON, DISTRICT OF COLUMBIA.

ELEVATOR SAFETY DEVICE.

1,278,726.

Specification of Letters Patent. Patented Sept. 10, 1918.

Application filed February 10, 1915; Serial No. 7,332. Renewed February 18, 1918. Serial No. 216,978.

To all whom it may concern:

Be it known that I, OMAR I. NIGH, a citizen of the United States, residing at Washington, in the District of Columbia, have 5 invented certain new and useful Improvements in Elevator Safety Devices, of which the following is a specification:

My invention relates to safety appliances for elevators, and contemplates a novel arrangement of parts whereby the elevator car is made to be inoperative when the shaft door is open, thus obviating the danger arising from elevator shaft doors being left open by the car operator after the car has 15 left the landing.

The object of my invention is to provide a device which will securely hold the door of the well shaft in a closed position, the fastening device of which can only be released by the car operator, and the means by which the lock of the door is released at the same time operates a contact whereby the current is broken.

Another object of my invention is to provide means by which it is impossible to open the doors of the elevator shaft while the car is at any point in the shaft other than directly in front of the door, and to unlock or release the door when the car has reached 30 the level of the landing.

A further object of my invention is to provide locking means for the door, secured upon the inside of the well shaft, and means located in the car on the opposite side of the door from that upon which the controller is located, to release the locking means, thereby compelling the operator of the car to assume a position immediately in front of the door, with one hand on the controller 40 and the other hand extended to the lock operating means, to hold the contact in operative position.

Finally, the object of my invention is to provide means whereby the current to the 45 elevator car is broken when the shaft door is moved to an open position and must be moved to a locked position before the car may again be started.

With the above and other objects in view, 50 the invention consists in the construction, combination and arrangement of parts, as illustrated in the accompanying drawing, forming a part of this specification, and particularly pointed out in the claims.

In the drawings:

Figure 1 is a view in elevation, showing

my improved locking device in an unlocked position.

Fig. 2 is a similar view, showing the lock in a locked position. 60

Fig. 3 is a view in elevation of the lock lever, out of engagement with the locking plate.

Fig. 4 is a view in elevation, showing the locking lever in engagement with the locking plate secured on the door. 65

Fig. 5 is a sectional view illustrating the position of the car operator when the car is in motion; the controller being upon one side of the car door frame and the lock operating lever upon the opposite side frame. 70

Fig. 6 is a sectional view of the shoe.

Fig. 7 is a perspective view of the door-locking plate.

Fig. 8 is a sectional view on the line 2—2 75 of Fig. 6.

Fig. 9 is a view of the contact collar.

Fig. 10 is a perspective view of the shoe.

Fig. 11 is a plan view of the contact mechanism, and 80

Fig. 12 is a sectional view of the contact mechanism.

In the drawings 1—1 indicate the landings of the elevator well shaft, and 2—2 the doors thereof, which may be of any ordinary construction. On the inner surface of the well shaft, adjacent the landings, I secure a bracket, 3, in any suitable manner. A lever, 4, provided at its upper end with a corrugated rectangular shaped extension, 5, and 90 at the opposite end with a track, 6, is pivotally mounted in the well shaft at each landing. A projection, 7, is formed integrally with the lever at its lower end, to prevent the lever from swinging out at the 95 top to be in the line of the car. On the floor, 8, of the elevator car I secure a support, 9, on which a hand lever, 10, is pivotally mounted. The lower end of the hand lever is provided with a shoe, 11, formed integrally therewith; the shoe, 11, being provided with flared ends, 12, which permit the shoe to be brought into a registering position with the track, 6, when it is desired to operate the locking lever, 4.

A collar provided with a contact piece, 13, is secured by means of a set screw, 14, to the hand lever, 10. A spring, 10', is also provided to automatically withdraw the lever should the operator remove his hand therefrom. A guide plate, 15, is secured at each end to the wall of the car upon one side of the hand lever, which 105 110

provides a guide for the hand lever so that the contact thereon may at all times be kept in line with a switch box, 16. The switch box, 16, is provided with two contact plates, 17 and 18, suitably secured to the bottom of the box casing; and to the upper inner surface of the box casing a support, 19, is secured. The front of the casing has an aperture provided with an insulating collar, 20, in which a spring actuated plunger, 21, reciprocates. On the plunger, 21, is a contact key, 22; the key, 22, being removable through the aperture, 23, in the switch box casing.

15 It will be noted that the contact is one of considerable length, the object of which will be hereinafter more fully explained.

A controlling device, 24, is located in the car in the usual position, but which in the 20 operation of my improved locking device is to be located upon the opposite side of the door frame from that upon which the means for releasing the well shaft door is located, as illustrated in Fig. 5 of the drawings. A 25 corrugated locking plate, 25, is secured to the inner surface near the bottom of a well shaft door, and immediately below the plate an elongated groove, 26, is provided. The object of the groove, 26, is to provide means 30 for a pin, 27, mounted on the lever, 4, to register therein when the door is in a locked position, and when the door is in an open position the pin, 27, cannot register with the groove, 26, and as illustrated in Fig. 1, the 35 contact is held in a broken position, thereby preventing the operator from obtaining current to move the car until the door has been moved in a closed position. The spring actuated plunger, 21, which carries the key, 40 22, is given a considerable degree of movement.

In the operation of my device, when the operator of the car desires to stop at any

landing, the hand operating lever, 10, is drawn back a sufficient distance to permit 45 the track to enter the shoe, and a further movement of the hand lever breaks the contact and at the same time the locking plate is released from engagement with the door locking plate.

50

It is believed that the operation, construction and arrangement of my improved elevator door safety locking device can be fully understood by the above description, it being noted that changes may be made in the 55 proportions and details, without departing from the scope of my invention.

What I claim as new and desire to secure by Letters Patent is:

1. In an elevator safety door lock, a lever 60 provided with a locking plate at one end and a track formed integrally therewith at its opposite end, suitably pivoted on the wall of the well shaft adjacent the landing, a lever having a flared end track shoe formed integrally therewith at its lower end, adapted to register with the track secured on the inner wall of an elevator shaft, as and for the purpose set forth.

65

2. In an elevator safety door lock, a lever 70 provided with a locking plate at one end and a track at its opposite end suitably pivoted to the inner wall of the well shaft adjacent the landing, a contact box, and a lever carried by the car, said lever having a flared end, and provided with a track shoe formed integrally with its lower end, a contact secured to the upper end of said lever adapted to register with a contact box secured to the car, as and for the purpose set forth.

75

In testimony whereof I affix my signature in presence of two witnesses.

OMAR I. NIGH.

Witnesses:

ALFRED D. SMITH,
JOE. C. BROWN.
